ABSTRACT: A machine for bowing out a side panel of a flexible carton formed with two end panels and two side panels so that the carton can be easily filled with a measured amount of product at a filling station. Each carton is moved at high speed with one end panel leading by a carton carrier along a first straight path, then along a curved path through a filling station, and then along a second straight path. The carrier is attached to a drive chain, and the chain is trained around a sprocket to establish the curved path through the filling station. Attached to the sprocket and extending radially outward therefrom are a number of pairs of pivoted fingers which travel in a path that is coextensive with the curved path of the cartons. As the cartons move along their path from the first straight portion to the curved portion, successive pairs of fingers move into registry with successive cartons. When in registry, the fingers of each pair are spaced on opposite sides of the end panels of the respective carton. Prior to filling of the cartons, the fingers of each pair are pivoted toward one another and into engagement with the end panels of the respective carton forcing the end panels toward one another and bowing out at least one of the side panels of the carton to open the latter widely for filling. After each carton passes through the filling station, the fingers are pivoted to spread positions and then moved out of registry with the carton.

MACHINE FOR FILLING CARTONS**BACKGROUND OF THE INVENTION**

This invention relates to a machine for filling flexible walled cartons and more particularly, to a machine in which the cartons to be filled have opposed end panels and opposed side panels and in which the cartons are advanced one at a time by a carrier through a filling station to receive a measured amount of product.

SUMMARY OF THE INVENTION

The primary aim of the present invention is to facilitate filling of the cartons by positively bowing the cartons to widely open positions during their advance toward the filling station and in a manner which enables advance of the cartons at faster speeds than has been possible heretofore and which, at the same time, avoids the danger of contaminating the insides of the carton during the bowing operation.

It is a related object to bow open the cartons by forcing the end panels toward one another thus bowing at least one of the side panels outwardly.

It is a further object to accomplish the above through the provision of novel pairs of pivoted fingers with the fingers of each pair being positionable on opposite ends of a carton and movable toward one another to engage the end panels of the carton to force the end panels toward one another and thus bow out at least one of the side panels.

Another object is to position the fingers alongside opposite end panels of the cartons in a novel manner as the cartons are moved toward the filling station.

Other objects and advantages of the invention will become apparent from the following detailed description taken in connection with the accompanying drawings.

BRIEF DESCRIPTION OF THE DRAWINGS

FIG. 1 is a fragmentary plan view of a carton filling machine embodying the novel features of the present invention.

FIG. 2 is an enlarged fragmentary cross section taken substantially along the line 2-2 of FIG. 1.

FIG. 3 is a perspective view of a bowed carton.

FIG. 4 is a fragmentary cross section on a reduced scale taken substantially along the line 4-4 of FIG. 2.

FIG. 5 is an enlarged fragmentary elevation taken substantially along the line 5-5 of FIG. 4, the carton being shown in phantom.

DETAILED DESCRIPTION OF THE PREFERRED EMBODIMENT

As shown in the drawings for purposes of illustration, the invention is embodied in a carton filling machine 10 (FIG. 1) operable to dispense measured amounts of material such as strawberries and their juice into upright cartons 11 (FIGS. 1 and 3) which are advanced continuously at a high rate of speed through a filling station 12 (FIG. 2) with their open ends passing beneath a discharge nozzle 13 to receive the material delivered to the nozzle from a suitable hopper or tank (not shown). After the cartons have been filled, their open ends are sealed closed, and the product is frozen within the cartons prior to shipment.

Each of the cartons 11 herein comprises a closed bottom and two opposed, resiliently flexible side panels 14 and 15 (FIG. 3) connected along opposite side margins to two narrow rectangular end panels 16 and 16a. To close the upper ends of the cartons, side flaps 17 and 18 and end flaps 19 and 20 projecting upwardly from the panels are folded across the upper ends. The closure flaps are resiliently hinged at 21 to the panels and normally assume upright positions until folded over and sealed closed.

In this instance, the cartons 11 are supported and advanced along a first straight path 22 (FIG. 1), then along a semicircular path 23 through the filling station 12 and beneath the discharge nozzle 13 and finally along a second straight path

24. The cartons are supported and advanced on an endless carrier comprising a pair of parallel horizontal chains 25 and 26 (FIG. 2) trained around vertically spaced lower and upper sprocket wheels 27 and 28 journaled on a frame 29 and suitably driven at a high rate of speed. The bottoms of the cartons slide on a stationary track 30 (FIG. 2) extending around the outside of and beneath the chains while the inner side panel 15 and the end panels 16 and 16a of each carton fit into and are carried by two vertically spaced holders 31 (FIGS. 1, 2 and 4) spaced equally along and connected to the outer sides of the chains. Each holder is formed with outwardly projecting legs 32 (FIG. 1) engaging the end panels and with a web 33 spanning the legs and supporting the inner side panel 15. To prevent the cartons from tipping outwardly, a curved horizontal rail 34 (FIG. 2) upstands from and is connected to the track and positioned alongside the semicircular portion 23 of the carton path to guide the side panels 14 as the cartons are advanced.

In accordance with the present invention, the end panels 16 and 16a of each carton 11 are forced toward one another just prior to the filling of the carton thus bowing out the side panel 14 to open the carton widely to receive a large amount of product in a short time interval and to receive product chunks larger than the unbowed thickness of the carton. For these purposes, pairs of fingers 36 (FIG. 4) are suspended beneath and pivotally supported by the upper sprocket wheel 28 with the fingers of each pair spaced apart and positionable on opposite sides of the end panels of a carton. The fingers of each pair may be pivoted toward one another to engage the end panels of the carton thus forcing the end panels toward one another and bowing out the side panel 14. With this arrangement, every carton, even though being advanced at a high rate of speed, will be bowed open prior to filling to facilitate the filling and this is accomplished with greatly reduced chances of interfering with the advance of the cartons. Further, such bowing is accomplished without the necessity of inserting any object into the cartons thus helping to maintain the insides of the cartons in an uncontaminated condition.

In this instance, each finger 36 is one portion of an L-shaped squeezer 37 (FIG. 4) which preferably is pivotally mounted to turn about a vertical axis by a pin 38 at the corner of the L on the horizontal leg 39 of an L-shaped support 40 (FIG. 2) whose other leg is vertically extending and connected by a pair of bolts 41 to the underside of the upper sprocket wheel 28. The other portion of each squeezer is formed as a pivot arm 42, (FIG. 4) which extends at a right angle from the finger. When parallel, the fingers of each pair of squeezers are spaced apart a greater distance than the distance between the end panels 16 and 16a of the cartons 11. From FIG. 4, it will be observed that the fingers extend radially outwardly from the pivot pins 38 a distance great enough that the free ends of the fingers can project beyond the outer margins of the cartons.

The squeezers 37 are paired with the pivot arm 42 of each pair extending toward one another and with the fingers 36 extending generally parallel to one another in their normal positions as exemplified by the fingers in FIG. 1 which are not between the cartons. Because the upper sprocket wheel 28 is driven by the chain 26, the pairs of the squeezers are moved along a circular path, half of which is coextensive with the semicircular path 23 of the cartons 11, and the squeezers are moved along the path in timed relation with the advance of the cartons. At the point at which the first straight path 22 becomes generally tangent to the circular path of the squeezers, the fingers 36 of each pair of squeezers move into registry with an advancing carton. From FIG. 1, it can be seen that one finger of each pair moves in front of the leading end panel 16 and the other finger moves behind the trailing end panel 16a. In the reverse manner, the fingers of each pair move out of registry with the respective carton when the semicircular carton path changes to the second straight path 24 and recedes along a tangent to the sprocket wheel. Thus, the fingers of each pair of squeezers encompass a carton as that carton moves along the semicircular path and through the filling station 12.

To effect the bowing of the cartons 11, the pivot arms 42 of each pair of squeezers 37 can be swung in unison to swing the free ends of the fingers 36 toward one another and into engagement with the end panels 16 and 16a of the carton disposed between the fingers. The outer end portion of a link 44 (FIG. 4) is pivotally connected to each pivot arm. The inner end portions of the pivot rods for each pair of squeezers are pivotally joined to one another and to the outer end portion of a cam rod 45 by a pin 45a, and the cam rod extends radially inwardly toward the axis of rotation of the upper sprocket wheel 28. A roller 46 (FIG. 4), rotatably mounted on the inner end portion of each cam rod extends upwardly therefrom and is seated in a cam track 47 (FIGS. 1, 2 and 4). The cam track is formed as a recess in a solid member 48 (FIG. 2) rigidly connected to the frame 29. The cam track is, as seen in FIG. 1, generally eccentric and is nearer the axis of rotation of the upper sprocket wheel 28 in the area of the filling station 12. With this arrangement, as each carton approaches the filling station, the associated cam rod is gradually pulled inwardly toward the axis of rotation by the cam track thereby pulling the pivot rods 44 inwardly to pivot the associated pair of squeezers 37 and swing the free ends of the fingers 36 toward one another just prior to the filling of the carton 11.

The swinging of the free ends of the fingers 36 toward one another brings them into contact with the leading end panel 16 and trailing end panel 16a of the carton 11 forcing these panels toward one another and bowing out the side panel 14 to open the carton widely for filling. From FIG. 4, it will be seen that the free ends of the fingers extend beyond the outermost side panels 14 of the cartons. As the fingers of each pair swing toward one another, the fingers initially contact the carton at the vertical junctions 50 (FIG. 4) joining the end panels to the outermost side panel 14 thereby causing the end panels to be forced toward one another along inwardly extending lines so as to help insure that the side panel will bow outwardly. To further insure that the side panel 14 will bow outwardly rather than inwardly, the side panels of the cartons are formed with a slight outward bow when made, and the memory of the material forming the cartons retains this slight bow.

Referring to FIG. 4, it will be observed that each cam rod 45 is slidably mounted through and suspended from the upper sprocket wheel 28 by a guide 51. The guide is formed in this instance by a rectangular block 52 (FIG. 5) connected at its upper surface to the underside of the upper sprocket wheel 28 by four bolts 54 (FIGS. 1 and 5), and a recess 55 (FIG. 5) just slightly larger than the cam rod is formed in the bottom of the rectangular block. To hold the cam rod within the recess, a cover plate 56 is connected by bolts 57 to the underside of the rectangular block. For access purposes, openings 57a (FIGS. 1 and 2) are formed in the upper sprocket wheel above each cam rod. Lubricant can be ejected into the recess 55 through a lubrication port 58 (FIG. 2) formed in the block 52.

The squeezers 37 are advantageously mounted on the L-shaped supports 40 so that one pivot pin 38 can be used to mount two squeezers. One squeezer of one pair is mounted either under or over the adjacent squeezer of the adjacent pair of squeezers, and the pivot pin extends through both squeezers to pivotally connect them to the support. In the present instance, the squeezers of the same pair are mounted on different levels. That is, one squeezer is the upper of two on one pivot pin and the other squeezer is the lower of two on the adjacent pivot pin.

It will be observed from the above that the utilization of 65 pairs of squeezers 37 registering automatically with and encompassing the advancing cartons 11 is a particularly advantageous arrangement since the cartons may be advanced, bowed, and filled at extremely high speeds. By bowing out the side panel of each carton externally with the squeezers, each 70 and every carton is positively bowed open without missing any cartons and without interrupting operation of the machine as a result of malfunctions or jamming. Since the bowing is achieved externally and without need of inserting any members into the carton, the danger of contaminating the inside of 75

the carton is reduced. Additionally, the mounting of adjacent squeezers of adjacent pairs of squeezers on the same pivot pin 38 helps reduce the overall cost of the machine.

I claim:

- 5 1. In a machine for filling cartons having opposed side panels, opposed end panels and open upper ends, the combination of, a frame, a carrier on said frame operable to support a succession of spaced cartons and advance the same open end up along a predetermined path through a filling station with one of the end panels of each carton forming the leading end of the carton, and means in a filling station for engaging the end panels and pressing one toward the other to bow at least one of said side panels of each carton away from the other side panel to spread the carton for receiving a charge of product at the filling station.

10 2. The machine of claim 1 in which said means comprise a pair of pivoted fingers, said fingers being movable in unison from positions out of engagement with the end panels to positions in engagement with the end panels.

15 3. In a machine for filling cartons having opposed end panels, opposed side panels and open upper ends, the combination of, a frame, a first carrier on said frame operable to support a succession of spaced cartons and advance the same open end up along a first predetermined path through a filling station with one of the end panels of each carton forming the leading end of the carton, a second carrier on said frame, at least one pair of opposed fingers each mounted on said second carrier to pivot about a vertical axis, said second carrier being operable to move said fingers along a second path coextensive with said first path from a point ahead of the filling station to a point beyond the filling station in timed relation with the advance of the cartons, and means operable when said paths are coextensive to pivot the fingers toward one another and into engagement with the end panels of one of the cartons to press the end panels toward one another and thereby bow at least one of said side panels away from the other side panel to spread the carton for receiving a charge of product at the filling station.

20 4. In a machine for filling cartons having opposed end panels, opposed side panels and open upper ends, the combination of, a frame, a first carrier on said frame operable to support a succession of spaced cartons and advance the same open end up along a first predetermined path through a filling station with one of the end panels of each carton forming the leading end of the carton, a second carrier on said frame, a number of pairs of opposed fingers supported on said second carrier with each finger being mounted to pivot about a vertical axis, the fingers of each pair normally being spaced apart a distance greater than the spacing between the end panels of each carton, said second carrier being operable to move said pairs of fingers in timed relation with the advance of the cartons along a second path which becomes coextensive with said first path from a point ahead of the filling station and which remains coextensive with said first path to a point beyond the filling station and being operable to move successive pairs of fingers into registry with successive cartons as said pairs of fingers and said cartons pass said point at which said paths become coextensive so that one finger of each pair is positioned ahead of the leading end panel and the other finger is positioned behind the trailing end panel of the respective carton as the latter approaches said filling station, and means therefore pivoting the fingers of each pair toward one another and into engagement with the end panels of the respective carton to press the end panels toward one another and thereby bow at least one of said side panels away from the other side panel to spread the carton for receiving a charge of product at the filling station.

25 5. In a machine for filling cartons having opposed end panels, opposed side panels and open upper ends, the combination of, a frame, a first carrier on said frame operable to support a succession of spaced cartons and advance the same open end up along a first predetermined path through a filling station with one of the end panels of each carton forming the

leading end of the carton, said first path being substantially straight to a first point ahead of the filling station, arcuate to a second point beyond the filling station and thereafter straight, a second carrier on said frame, a number of pairs of opposed fingers supported on and spaced along said second carrier with each finger being mounted to pivot about a vertical axis, said fingers of each pair normally being spaced apart a distance greater than the spacing between the end panels of each carton, said second carrier being operable to move said fingers in timed relation with the advance of the cartons along a circular path having a portion coextensive with said arcuate portion of said first path and being operable to move successive pairs of fingers into registry with successive cartons as said pairs of fingers and said cartons pass said point at which said paths become coextensive so that one finger of each pair is positioned ahead of the leading end panel and the other finger is positioned behind the trailing end panel of the respective carton, means operable thereafter to pivot the fingers of each pair toward one another and into engagement with the end panels of the respective carton to press the end panels 20

toward one another and thereby bow at least one of said side panels away from the other side panel to spread the carton for receiving a charge of product at the filling station, means operable after the carton has been advanced beyond the filling station for pivoting said fingers away from one another to release the filled carton, and said second carrier thereafter being operable to move said pairs of fingers out of registry with the filled cartons as the cartons move past said second point thereby to free the filled carton.

5 10 15

6. The machine of claim 5 in which said second carrier is a circular member mounted to rotate about a vertical axis, said pairs of fingers being angularly spaced about the periphery of said member, and further including a pivot member mounting one finger of each pair and the adjacent finger of the adjacent pair to pivot about a common vertical axis.

7. The machine of claim 5 in which said means to pivot the fingers of each pair includes an actuator common to each pair and pivotally connected to each of said fingers.
